his Attorney.

UNITED STATES PATENT OFFICE.

WALTER F. WARE, OF CAMDEN, NEW JERSEY.

NIPPLE-HOLDER.

SPECIFICATION forming part of Letters Patent No. 651,497, dated June 12, 1900.

Application filed October 13, 1899. Serial No. 733,476. (No model.)

To all whom it may concern:

Be it known that I, WALTER F. WARE, a citizen of the United States, and a resident of Camden, State of New Jersey, have invented certain new and useful Improvements in Nipple-Holders, of which the following is a full, clear, and exact description, reference being had to the accompanying drawings, forming part of this specification.

10 My invention has relation to the construction of a device comprising, essentially, a rubber nipple adjusted upon a handle for babies' use; and it consists in the construction hereinafter particularly described and claimed.

15 The object of my invention is to provide a neat, strong, and effective nipple-holder and one which may be readily attached, as hereinafter described, to the child's wrist to prevent dropping, breakage, or loss.

20 In the accompanying drawings, Figure 1 is a perspective view of my improved "comforter." Fig. 2 is a longitudinal sectional view illustrating the construction and method of securing the parts together. Fig. 3 is a

25 cross-sectional view through the handle, illustrating the position of the cords in the orifice provided therethrough.

A represents a hollow rubber nipple with solid walls open only at the point of connection with the handle to which it is secured.

The handle B, which is preferably about an inch or an inch and a half long and usually constructed of bone or other suitable material, is provided at the connecting end with

35 two enlarged rings or bosses b b', preferably integral with the handle, forming a recess or seat c, in which the narrow neck e, forming the walls around the opening of the nipple, is adapted to be seated and to snugly fit, the

40 diameter of this opening of the nipple being preferably slightly less than the diameter of the recess or seat c. The circular guard or button g, preferably of bone or similar material to the handle B, is provided centrally

45 with an orifice g' of a diameter slightly less than the exterior diameter of the neck e of the nipple and when placed thereon holds the neck e firmly in position in the seat c, preventing accidental displacement. Enlarged

50 lips c' are provided upon the outermost part of the neck e, abutting between the inner face of the ring b and face of the disk g, thereby

tending to effect a tighter joint and to hold the parts more securely and firmly together.

Through the center of the handle B, I provide a longitudinally-disposed orifice o, extending from the interior of the nipple A to and through the extreme outer end of the handle, for a twofold purpose—first, to allow the air in the bulb of the nipple when the 60 nipple is compressed to freely escape and to thereby allow the nipple to be readily compressed and to freely expand when released, and, secondly, to provide a passage and means of neatly and securely holding the cord d for 65 attaching the comforter to the wrist of the child to prevent it from being dropped and lost or broken. The cord d being doubled, as shown, is passed through the orifice o and knotted on the inner end within the walls of 70 the nipple, so as to prevent the cord from being pulled out and to hold it securely in place, and the knot is so arranged as not to interfere with the free passage of the air, the orifice o being of sufficient diameter to 75 allow the two strands of cord to freely pass therethrough and at the same time to leave around the cords sufficient vent for the passage of the air to and fro as the nipple is compressed and expanded. It is clear from the 80 construction illustrated and described herein that the cord b is capable of some longitudinal movement in the air-channel, which operates to prevent the clogging of the external mouth of the air-channel with foreign matter 85 and in this manner always allows a sufficient ingress and egress passage for the air in its travel to and from the nipple-chamber. This feature is important and overcomes objections heretofore existing in former constructions. The opposite end of the cord d is formed in a loop or the outer ends otherwise united, and intermediate in its length I provide a short circular sleeve or ring h, having an orifice p, longitudinally disposed there- 90 through, of a diameter slightly less than the greatest diameter of the two cords when in position, so as to slightly compress the cords in order that the ring h may be retained at any given position, so as to prevent the looped end from slipping off the child's wrist when placed thereon, while at the same time it may be readily slipped along to disengage the loop 95 when desired.

The parts may be readily adjusted in assembling, the disk or button *g* being first passed over the narrow neck *e* or opening of the nipple by slightly compressing the same 5 and pushing the disk slightly back upon the nipple, then adjusting the neck *e*, with the lips *c'*, in position upon the seat *c*, and then slipping the disk or button *g* back against the lips *c'* into the position illustrated in Fig. 10 2 for holding and securing the parts together, as described.

I am aware that nipple-holders of different constructions have heretofore been invented having the rubber nipple adjusted in position 15 upon a short handle, and do not claim the same broadly. I aim in my invention to overcome certain defects heretofore existing in the construction and operation and limit myself to the device described. In my invention 20 the nipple is not only firmly and securely held in position, but a free exit and ingress for the passage of the air is provided centrally and longitudinally through the handle without liability to becoming clogged and 25 without weakening to any material degree the device, the passage of the double cord through the handle tending to prevent the ingress of foreign matter so as to clog the orifice and at the same time allowing sufficient 30 air-space around the cords and the inner walls of the orifice to enable a free passage. It is also clear that with the cord centrally disposed through the handle the handle is per-

fectly free to be readily and comfortably grasped without interference from the cords. 35

Having thus described my invention, what I claim, and desire to secure by Letters Patent, is—

A nipple-holder, comprising a compressible rubber nipple, a handle having a longitudinally-disposed combined cord and air channel provided centrally throughout the entire length of the said handle communicating with the nipple-chamber, a flexible securing-cord passing through said channel secured at the 40 inner end to prevent the withdrawal of the cord yet capable of some movement longitudinally within said air-channel sufficient to prevent the external opening of the air-channel from becoming clogged at its mouth with 45 foreign matter, said longitudinally-disposed channel being of greater area in cross-section than the area of the cord in cross-section operating as a combined cord passage and duct for the ingress and egress of air to and from 50 the nipple-chamber, and a guard provided around the neck of said nipple about the point of connection with said handle, substantially 55 as described.

In witness whereof I have hereunto set my 60 hand this 9th day of October, A. D. 1899.

WALTER F. WARE.
